Augustus Jess Bowe

UNITED STATES PATENT OFFICE.

AUGUSTUS JESSE BOWIE, OF SAN FRANCISCO, CALIFORNIA.

OIL CIRCUIT BREAKER.

Application filed December 5, 1921. Serial No. 520,095.

To all whom it may concern:

Be it known that I, AUGUSTUS JESSE BOWIE, a citizen of the United States, residing at San Francisco, county of San Francisco, State of California, have invented certain new and useful Improvements in Oil Circuit Breakers; and I do hereby declare the following to be a full, clear, and exact description of the invention, such as will enable others skilled in the art to which they appertain to make and use the same.

It is the object of this invention to provide improvements in oil circuit breakers.

The invention has reference to the design of the circuit breaker proper for operation under oil, and to the mechanism for tripping and opening the same. The underlying principles governing the successful operation of an oil circuit breaker, are:

20 First: That there must be a sufficient head of oil over the break to extinguish the arc promptly, and

Second: That the motion of the break, particularly when the blade leaves the following contact, must be rapid.

In my breaker the arc is interrupted in a horizontal plane, thus providing the maximum possible depth of oil over the break without increasing the depth of the tank. 30 The arrangement is such that the inertia of the moving parts is reduced to a minimum, and the initial part of the break is accomplished very quickly thru a combination of mechanisms outlined hereafter.

35 Fig. 1—is a plan view in section of the breaker along line (A. A) of Fig. 2.

Fig. 2—is a sectional view of the breaker along the line (B. B.) of Fig. 1, one of the two main insulators entering the tank being shown in projection.

Fig. 3—is a plan view of the trip mechanism.

Fig. 4—is an elevation of the same.

45 Fig. 5—is a plan view showing a general arrangement of the 3 poles of a 3 pole breaker, together with the trip mechanism.

Fig. 6—is a diagrammatic plan of the mechanism of the breaker in the tank, showing the position of the blades when open and closed.

Fig. 7 is a plan view of the breaker with the blades in open position, corresponding to Fig. 1, which is in closed position.

45 (1) is the casing for holding the oil of the breaker, (2) is the top of the breaker, (3, 3) are the main insulators carrying the

entering and outgoing leads from the breaker; (4, 4) are conductors for carrying the leads thru the centers of insulators (3, 3) to the switch terminals in the lower part of the case. (5, 5) are flanges cemented to insulators (3, 3) adapted to secure them by pieces (53, 53) to flanges in cover 2, for supporting the insulators thereon. (6) is a cast iron support attached to top (2), (7) is a crank, (8) is a crank pin, (9) a connecting rod, (10) a shaft fast to crank 7, (11) is a coupling secured to shaft 10, and also to rod (12) which may be made of wood or other insulating material, (13) is an insulating tube rigidly supported in cap 6, provided with cap 14, at its lower end, (15) is a crank attached to the lower end of rod 12, provided with two clevis type ends in which the link ends (16) are pivoted by pins 18. Connected thereto are adjustable link ends (17, 17), which connect to hinged blades (20, 20) thru pins (19, 19). (21, 21) are main clips, preferably made of wedge type mounted in turn on the supports (23, 23) which are secured to supporting flanges (24, 24) secured in turn to the lower end of insulators (3, 3) and electrically connected to conductors (4, 4). (22, 22) are follower contacts, which as shown, make a surface contact with the ends of blades 20, 20, so that the blade has to travel to the end of said contacts before the arc starts to break. These contacts may be either made in the form of parallel plates or may be made with a spring follower which will contact with the inner edge of the end of the blade—a type which is common with circuit breakers. (26, 26) are projections from cap 14, provided with slots or corresponding supporting and current carrying attachments for blades 20, 20, which as shown are secured thru pins (25, 25). The type illustrated is similar to the usual type of hinge end for a switch blade.

In Figs. 3, 4 and 5; 27 is the trip shaft supported in bearing 29, attached to supporting base 28. (30) is a stop for limiting the motion of the mechanism for opening the breaker which is made approximately 180°; (31) is a crank rigidly attached to shaft 27 carrying an arm 32, on the outer end of which is a forked lever (36) provided with a pinion roller 37, operating on pin 38; 36 is pivoted by pin 39 on arm 32. 35 is a crank loosely mounted on shaft 27 and carrying a bossed portion in which

the pin 34, is secured; it is also provided with an arm, 33. The connecting links 9, 9 connect the different poles of the breaker together, the type shown herein having each 5 pole in a separate casing. In Figs. 4 and 5 the outer ends of link 9 are attached to pin 34, and the motion of the shaft 27, thru approximately 180° operates the different 10 poles of the breaker simultaneously. The roller 37, engages the outer end of arm 33, and is held in engagement by the light spring 49, one end of which is attached to arm 32, and the other end to piece 36.

50 is the stop on arm 32 limiting the motion 15 of the piece 36, when disengaged from arm 33. Arm 33, however, as shown is provided with a bossed portion at the end which limits the position of roller 37, when in engagement therewith. (40) is a spring 20 adapted to open the breaker, pressing against collar 48, the inner end being held by piece 47, which has a slotted hole for rod 9 and is attached to base 28; (41) is the outer end of piece 36; (42) is a limit stop 25 attached to the base 28 adapted to limit the motion of crank 31 on the closing of the breaker. (43) is a latch mounted in piece 44 and pressed forward as shown by spring 45, mounted on lug 46, secured on base 28.

30 Fig. 6 shows in principle the diagrammatic operation of the mechanism within the breaker tank, the full line showing the breaker closed and the dotted line showing the breaker in open position.

35 One important feature of this breaker is the fact that when in open position the blades conform very closely to the limit of the supporting mechanism, thus keeping the width of the tank within reasonable limits.

40 A study of the operating mechanism as shown indicates the following very important features:

In the closed position the crank 15, together with links connecting to the blades 45 form a toggle connection thus giving a maximum pressure to hold the blades in the contact clips with the minimum strain on the operating mechanism. The piece 11, is flexibly connected to shaft 10, and the 50 lower end of rod 12, rigidly connected to the hub of crank 15, plays loosely in cap 14. This allows equalization of the strains on the two blades by allowing a small motion at the lower end, if the strains tend to be unequal. This equalizer is obviously of considerable importance. It is evident that the 55 cap 14, is subject to very little strain in the switch operation since the major portions of the strains are self-contained and pass directly thru the metal from one side to the other, thus minimizing the mechanical strains of operation.

The initial movement of the breaker in 60 opening blade 20, is slow, due to the toggle action. However, a study of the mecha-

nism as outlined shows that by the time the blade has reached the outer end of the clip 22, at which point the contact is finally broken, this toggle is entirely done away with and the motion is extremely rapid for 70 a small angle of motion of the operating rod 12. This very desirable result secures a maximum speed just where it is required.

Most of the inertia of the moving parts 75 lies in the blades 20, 20, which are short and light, and hence allow great rapidity of action. These blades may, if desired, be provided with limit stops striking against each other, which tend to prevent jar when the breaker is opened, thus pieces 51, 51, with 80 bumpers 52, 52, form opposing limits for striking together when the blades are open.

Horizontal break switches of different 85 types have been used before, but the principles involved herein, the avoidance of inertia and the simplicity of operation make my switch particularly desirable.

With reference to the operating mechanism, Figs. 3, 4, and 5 show the breaker in the closed position. Spring 40 which 90 presses thru the rod 9, on pin 34, is slightly off center of the full closed position and tends to turn crank 35, which however, is held from turning by roller 37, attached thru pins 38, 39 and piece 36 to arm 32 and 95 crank 31. Crank 31 is held from opening by latch 43. The automatic trip mechanism for opening the breaker, (not shown herein, as there is nothing new involved in this mechanism in my breaker) strikes lightly 100 against 41, in a downward direction. A comparatively small, pressure is required to make roller 37 slip off the end of arm 33, since not only is the torque of spring 40, 105 about shaft 27 made comparatively light, but the roller arrangement is such as to cut down to a minimum the power required for operation.

When the arm 33 is released from roller 110 37, spring 40 will cause it to open and travel thru nearly 180° the outer end of the stroke being limited by arm 33 impinging on stop 30. This motion thru 180° is very desirable, 115 since at the open end of the stroke the crank going thru dead center has taken care of the motion of all the moving parts of the breaker, except the inertia of arm 33, and minor other parts so that the hammer blow on the stop is quite light. While it might 120 seem at first glance, objectionable to have a travel of 180° on the ground that it would make too slow an initial break of the breaker, yet a study of the mechanism as laid out, shows that this is not the case, and 125 that the connecting rod 9, will have attained nearly its maximum speed at the moment the breaker blade actually leaves the clips.

The small lever arm of rod 9 in the closed 130 position around the shaft 27, results in comparatively light pressure against the roller

37, minimizing the power required for the trip of the breaker. To release the breaker manually the details of the trip are not shown, as they do not form a part of the 5 patent, but this can be readily accomplished by the manual trip first pressing against lever 41 and then opening latch 43, allowing the breaker to open of itself and the operating handle to be opened either by a 10 spring or by other means.

What I claim is:

1. In an oil circuit breaker a pair of electrically connected blades hinged on different axes for opening and closing the 15 circuit, adapted to be substantially parallel throughout their travel, said blades operating in opposite directions.
2. In an oil circuit breaker a pair of electrically connected blades, adapted for 20 opening and closing the circuit, a supporting member in which said blades are rotatably mounted, the outer end of each blade being in proximity to the supporting end of the other blade when the breaker is open.
- 25 3. In an oil circuit breaker, a pair of electrically connected blades adapted to open and close the circuit, a central supporting member in which said blades are separately hinged on different axes, and 30 means for opening and closing said breaker thru the operating of said blades which are adapted to remain substantially parallel at all points of the stroke.
4. In an oil circuit breaker a pair of electrically connected blades adapted to open 35 and close the circuit by rotation in the same direction, a supporting structure on which the ends of said blades are separately mounted and a central rotating member adapted 40 to operate said blades.
5. In an oil circuit breaker a pair of electrically connected blades adapted to open 45 and close the circuit by rotation in the same direction, a supporting structure on which said blades are separately mounted, links connecting with said blades, and a central rotating member adapted to operate said blades thru said links.
6. In an oil circuit breaker a pair of 50 blades adapted to open and close the circuit, an insulated supporting structure in which said blades are separately mounted, links connecting with said blades and a central rotating member adapted to operate said blades thru said links, said blades being substantially parallel at all points of the stroke.
7. In an oil circuit breaker, a pair of pivoted electrically connected blades adapted to 60 operate said breaker by rotation in the same direction, a pair of pivots, supports for said pivots, and a central rotating shaft adapted

to operate said blades, thereby opening and closing the breaker.

8. In an oil circuit breaker, a pair of 65 blades separately pivoted on a supporting member and adapted to operate in the same rotational direction, a central operating shaft having a pair of cranks at the lower end thereof, links connecting said cranks to 70 said blades, the mechanism being adapted to open and close the breaker.

9. In an oil circuit breaker a pair of 75 electrically connected blades, supports for same in which said blades are separately pivoted, a central operating shaft provided with two cranks, a pair of links connecting said cranks to said blades, the links and cranks constituting substantially a toggle mechanism when the breaker is closed.

10. In an oil circuit breaker, a pair of 80 electrically connected blades for opening and closing the circuit, a central supporting member on which said blades are pivotally mounted, in combination with a central operating member adapted to operate said blades, said supporting member and said operating member being co-axial.

11. In an oil circuit breaker a pair of 85 electrically connected blades for opening and closing the circuit, a tubular supporting member on which said blades are pivotally mounted, in combination with an operating member adapted to operate said blades, said tubular member and said operating member being co-axial.

12. In an oil circuit breaker a pair of 90 blades for opening and closing the circuit, a tubular supporting member on which said blades are pivotally mounted, in combination with an operating member operating within said tubular member, said operating member being adapted to operate said blades.

13. In an oil circuit breaker a pair of 95 blades for opening and closing the circuit in combination with bumpers on said blades, said bumpers being adapted to impinge on each other when the breaker is opened, thereby limiting the motion and taking care 100 of the inertia of said blades.

14. In an oil circuit breaker, a pair of 105 separately pivoted blades adapted to open and close the circuit, a rotating shaft adapted to operate said blades, a loose fitting bearing for said shaft adapted to allow equalization of the pressures of closure on said blades.

In testimony whereof, I affix my signature, in the presence of two witnesses.

AUGUSTUS JESSE BOWIE.
